UNITED STATES PATENT OFFICE.

JOHANN EDUARD TANNENBAUM, OF WILMERSDORF-FRIEDENAU, GERMANY, AS
SIGNOR TO GENERAL ELECTRIC COMPANY, A CORPORATION OF NEW YORK.

HOT-WATER-STORAGE APPARATUS FOR STEAM PLANTS.

Application filed November 22, 1923. Serial No. 676,448.

To all whom it may concern:

Be it known that I, JOHANN EDUARD TANNENBAUM, a citizen of the Republic of Switzerland, residing at Wilmersdorf-Friedenau, Germany, have invented certain new and useful Improvements in Hot-Water-Storage Apparatus for Steam Plants, of which the following is a specification.

This invention relates to hot water storage apparatus and more particularly to hot water storage apparatus adapted to steam power station installations in which heated vapor chambers are provided with a water cooling means.

It is the object of this invention to provide an improved means in conjunction with a cooling apparatus for a heated vapor space for automatically extracting hot water from said apparatus and supplying the same automatically to a storage tank at a certain uniform predetermined temperature.

For a consideration of what is believed to be novel and the invention, attention is directed to the accompanying drawing, description thereof and the appended claims.

In the drawing, a portion of a power plant installation provided with an arrangement in accordance with the invention for obtaining and storing hot water is diagrammatically represented.

Referring to the drawing, 1 is a steam turbine supplied with steam through an inlet 2 and exhausting through a conduit 3 into a surface condenser 4. The turbine is shown connected to an electric generator 5. The turbine, generator and condenser may be taken as representing the usual power plant prime mover installation.

The surface condenser 4 is supplied with cooling water from a cold water source indicated at 6, such as a well, being connected therewith by a conduit line 7 in which is located a suitable circulating pump 8. A strainer 9 is fitted over the intake end of this conduit line to exclude foreign matter which would damage the pump and condenser. The pump draws cooling water from the supply source 6 and forces it through the condenser in the usual system of parallel cooling water tubes indicated at 10, to condense the steam delivered from the turbine to a vacuum chamber 11 which surrounds said cooling water tubes. A valve 12 is placed in conduit line 7 between the

pump and the condenser for throttling the cooling water supply when desired.

The cooling water passes from the condenser through a discharge conduit 13 to a free outlet 14 from which it may flow to any suitable drain. The condenser installation may be considered as any available heated vapor space through which a cooling liquid is passed in a conduit line for cooling purposes. At 15 is a storage tank for hot water which is to be used in other operations of the plant, the supply for said operations being taken from the bottom of the tank through a conduit 16 connected therewith. A cover 17 for the tank is provided to reduce heat losses by evaporation and in certain cases the tank may be lagged with heat insulation to reduce radiation losses.

The storage tank is supplied with warm water, in the present example, from the cooling water outlet of the condenser, through a conduit 18 which is joined by a T-connection 19 with the discharge conduit 13. This conduit leads into the top of tank 15, passing through the cover 17, and discharges above the water level. The water level is preferably kept high and within limits which will insure a constant supply to outlet conduit 16, and is here shown as midway between such limits with the tank approximately half full.

For automatically maintaining the water level between the desired limits, a float 20 is provided within the tank to follow the variations in water level and is shown by way of example as electrically controlling the opening and closing of a valve 21 located in a casing 22 inserted in the discharge conduit 13 between the T-connection 19 and the cooling water outlet 14. The valve 21 is shown as a sliding gate valve but may be of any type which may be controlled by the float 20.

The closing of valve 21 stops the normal outflow from the condenser, and the cooling water then finds an outlet by way of conduit 18 to the storage tank. However, it is prevented from flowing to the tank until its temperature has reached a certain predetermined higher value by means which will hereinafter be described.

The operating means between float 20 and the valve 21 comprises a reversible motor

23 mounted adjacent valve 21, a gearing 24 connected with the motor and a valve stem 25 threaded through the axis of one of the gearing members. The arrangement is such 5 that rotation of said member by the motor moves the valve stem up or down to operate the valve.

A pair of spring closed limit switches 26 and 27 are connected in circuit with the 10 motor. These are arranged adjacent valve 21 in a position to be struck and opened by an insulated arm 28 carried by valve-stem 25 as the valve and valve-stem reach the 15 end of their opening or closing travel. The opening of either switch serves to stop the motor by opening the supply circuit. Switch 26 is in the circuit through which the motor receives current when opening the 20 valve and switch 27 is in the circuit through which the motor receives current in closing the valve. In the drawing valve 21 is shown in the normal open position at the limit of its travel with arm 28 holding switch 26 open.

25 The motor receives current from mains indicated at 29 through a connecting cable 30 and a reversing switch 31. This switch controls the operation and direction of rotation of the motor and is located adjacent tank 15.

An operating lever 32, with which the switch is provided, may be moved downwardly, as shown in the drawing, to operate the motor in a direction to open the valve 21 35 or upwardly to operate the motor and close the valve 21. By means of a cord 33 passed over idler pulleys 34-34 and connected with the float and an adjustable balancing weight 35, movement of the float effects the operation 40 of the switch automatically. The cord 33 passes through a ring at the end of lever 32 and a pair of stop lugs 36 and 37 are secured to the cord above and below this ring at distances from it to allow any desired 45 variation in movement of the float before the switch is actuated by the stop lugs as the float moves in following the water level in the tank.

50 In conduit 18, which connects cooling water discharge conduit 13 with the tank 15, is a valve casing 38 in which is located a sliding gate valve 39. This valve is normally closed as shown and is provided with a sliding valve stem 40 by which it is operated. A piston 41 carried at the outer end of this valve stem and fitted within a cylinder 42 is pressed on one side by a compressed spring 43 to move the valve to the closed position and on the other side by the pressure of a liquid 44 to move the valve to the open position. Normally, the spring exerts the greater pressure and maintains the valve in the closed position. It is adjusted to yield at a certain point as increased pressure is applied to the liquid, permitting the

valve to gradually open. The valve shown is to be taken as representing any suitable valve capable of being operated by a sliding valve stem.

The pressure applied to the liquid 44 and 70 to the piston 41 is that existing in the vapor space 11 of the condenser 4. A cylinder 45 is arranged vertically on the condenser to open at one end into the vapor space 11. The 75 opposite end of cylinder 45 is closed and connected by a pressure conduit 46 with the liquid in cylinder 42. A movable abutment 47 within the cylinder 45 serves as a movable dividing wall between the vapor space 11 and the liquid from cylinder 41 which fills 80 pressure conduit 46 and the cylinder 45 above said abutment. A compressed spring 48 in the upper end of cylinder 45 is adjusted to exert sufficient pressure on the movable abutment 47 to cause the same to return 85 to its lower or normal position as shown when the pressure exerted on it from the vapor space 11 is normal. A sufficient quantity of the liquid 44, which may be oil, or 90 water, is supplied to the system to completely fill the cylinder spaces provided for it and the conduit 46 when the piston 41 and abutment 47 are in their normal positions as shown.

The operation of the system is as follows: With turbine 1 and pump 8 in operation, mains 29 energized, and valves 21 and 39 in their normal positions as shown, as water is drawn from tank 15 through outlet conduit 16 the water level falls until 100 stop lug 37 strikes the ring on the end of switch lever 32 and carries said switch lever to the upwardly closed position.

105 Motor 23 then operates and closes valve 21, cutting off the cooling water outlet 14. As valve 39 is also closed there is no outlet for the cooling water from the condenser. Pump 8 continues to operate so that the cooling water in the condenser is trapped and becomes heated above normal. As the 110 trapped cooling water becomes heated to a higher degree the pressure in the vapor space increases because the cooling water does not then condense all of the steam supplied from the turbine exhaust 3. This 115 increased pressure is applied to the movable abutment 47 and through the medium of the liquid 44 is transmitted to piston 41. Spring 43 finally yields at a predetermined point as the pressure increases and permits valve 39 to open sufficiently to allow the heated cooling water to flow through T-connection 19 and conduit 18 into the tank 15. The valve opens gradually and only 120 as the pressure increases. The temperature of the cooling water permitted to pass to the tank is controlled by the strength of spring 43, as it does not yield and allow valve 39 to open until a certain pressure is exerted on the opposite side of the 125

piston 41 and as this pressure is supplied from the vapor space 11 in which a pressure determined by the temperature of the cooling water exists, it is seen that the water supplied to tank 15 by this arrangement will have a certain predetermined constant temperature. That is, as the trapped cooling water is unable to condense the steam, the pressure in the condenser increases as the cooling water increases in temperature. Valve 39 opens to pass the heated water to the storage tank 15 only when a certain predetermined pressure is reached in the condenser and as the cooling water must reach a certain corresponding temperature before this pressure can exist, a definite setting for the opening of valve 39, by employing a spring of the proper strength at 43, also definitely determines the temperature of the water supplied to the storage tank 15. The initial temperature of the cooling water and the load on the turbine have only the effect of changing the rate at which the tank is filled and not any effect on the temperature of the water delivered thereto.

As the tank is filled, the float 20 follows the water level and stop lug 36 finally comes into contact with the ring end of lever 32, carrying said lever to the downwardly closed position. Motor 23 operates to open valve 21. The cooling water then flows through the condenser at the normal rate to the outlet 14 and the pressure quickly decreases in the vapor space 11 with the result that valve 39 closes and the plant operates normally until the supply of hot water in tank 15 falls to the lower limit again when the operations just described automatically repeat.

In the present apparatus for obtaining hot water in accordance with the invention, the water flow from the condenser is entirely interrupted or stopped and connection established with the water storage tank only when the pressure in the condenser has increased to a value corresponding to the desired water temperature, such temperature being usually set to cause the least possible change in the temperature of the water already in the tank.

The arrangement in any case is, in accordance with the invention, such that a storage tank or other receptacle for hot water will be refilled automatically, when emptied to a predetermined level, with hot water of a certain predetermined temperature, independently of the initial water temperature or of the amount of heat available. It may be applied to existing steam plant installations, provided that in any installation the hot water temperature required is not such that the corresponding pressure to be set up in the condenser vapor space to produce it will injure the condenser or result in an undesirable decrease

in the power output from the prime mover exhausting into said condenser. It is this that limits the temperature at which the hot water may be supplied to a storage tank.

It may be applied to other installations having available a heated-vapor space through which a cooling liquid is passed in a conduit and in which installations an increased pressure in the vapor space and partial or complete stopping of the cooling liquid flow is allowable.

In accordance with the provisions of the patent statutes I have described the principle of my invention, together with the apparatus which I now consider to represent the best embodiment thereof, but I desire to have it understood that the apparatus shown is merely illustrative and that the invention may be carried out by other means.

What I claim as new and desire to secure by Letters Patent of the United States, is:—

1. The combination with a surface condenser having a cooling water outlet and a vapor space, of a valve in the cooling water outlet, a hot water storage tank, means actuated by the water level therein for controlling said valve, a conduit connection between the cooling water outlet and the storage tank, a valve in said conduit connection, and means connected with the condenser vapor space and actuated by the pressure therein for controlling said last named valve.

2. In a hot water storage apparatus comprising a condenser having a cooling water outlet and a hot vapor space, the combination of a hot water storage tank, a conduit providing a connection between the cooling water outlet and the storage tank, a second conduit connecting the cooling water outlet with the atmosphere, a normally closed valve in said first-named conduit, a pressure responsive means connected with the condenser vapor space and said valve to open the latter in accordance with increasing pressure valves in said vapor space above a certain predetermined limit, a normally open valve in the second-named conduit and a float controlled means responsive to changes in the water level in the storage tank operatively connected with said last-named valve.

3. The combination with a surface condenser having a cooling water outlet and a vapor space, of a valve in the cooling water outlet, a hot water storage tank, means actuated by the water level in said tank for controlling the valve, said means including a float in the tank, a reversible motor operatively connected with the valve, a reversing switch controlling the motor, and a stop controlled connection between the float and the switch whereby the float controls the operation of the valve, a conduit connection between the cooling water outlet and the storage tank, a valve in said conduit con-

nection, and means including a movable piston connected with the condenser vapor space and actuated by the pressure in said vapor space for controlling said last-named valve.

4. The combination with a surface condenser having a cooling water outlet and a vapor space, of a valve in the cooling water outlet, a reversible electric motor operatively connected with said valve for opening and closing the same, a reversing switch for the motor, a hot water storage tank, a float in the tank responsive to changes in water level therein, means provided with adjustable stops for connecting the float with the switch to actuate the latter, said switch being actuated thereby to cause the motor to close the valve when a certain predetermined lower water level is reached, and said switch being actuated thereby to cause the motor to open the valve when a certain predetermined higher water level is reached, a conduit connection between the cooling water outlet and the storage tank through which cooling water flows when said valve is closed, a second valve in said conduit and pressure responsive means connected with the condenser vapor space operatively controlling said second-named valve.

5. A hot water storage apparatus comprising a conduit through which a liquid flows, a heated vapor space through which said conduit passes, a hot water storage tank, a conducting pipe providing a connection between the storage tank and the conduit, said conducting pipe joining the conduit at a point succeeding the vapor space in the direction of flow, a waste outlet for the conduit succeeding the point of connection of the conducting pipe to the conduit in the direction of flow, a valve in the conduit adjacent the waste outlet for controlling the discharge therefrom, means including a float in the storage tank for operating the valve when certain predetermined limits in liquid level are reached, a certain lower level effecting a closing of the valve and a certain higher level effecting an opening of the valve, a normally closed valve in the conducting pipe, and means responsive to pressure in the vapor space connected with said last-named valve and operating to open the same when a certain predetermined pressure limit is exceeded.

In witness whereof, I have hereunto set my hand this 31st day of October, 1923.

JOHANN EDUARD TANNENBAUM
